UNITED STATES PATENT OFFICE

2,280,007

SAFETY GUARD FOR PNEUMATIC CHIPPING
HAMMERS AND THE LIKE

Stephen Plateck, Youngstown, Ohio

Application March 12, 1940, Serial No. 323,615

6 Claims. (Cl. 30—168)

This invention relates to a safety device and particularly to an improved safety guard for the use of workmen operating chipping hammers and the like.

Heretofore, operators of pneumatic chipping hammers and the like usually wore goggles to protect their eyes from injury, due to flying chips or other foreign particles. While goggles are satisfactory and are a good protection for the eyes, they do not protect the face and other parts of the body of the operator from injury, nor nearby workmen engaged in other duties. Also, it is necessary for the chipping hammer operators to wear goggles the greater part of the day, and they become quite uncomfortable to the wearer after continuous use over such a long period of time.

It has been proposed to attach safety guards directly to the body or barrel of the pneumatic hammer, but such guards are unsatisfactory in that the support for the guards is positioned too far from the point of cutting and the guards are readily forced out of adjustment and from over the point of cutting or chipping due to the vibration of the hammer which is, of course, unsatisfactory. Further, such guards attached to the hammer made the hammer bulky and oftentimes interfered with the operation thereof, thereby tending to discourage their use entirely, which of course defeated the purpose for which they were intended.

According to the present invention, there is provided an improved safety guard which is at all times maintained in position directly over the workpiece and the cutting tool and, at the same time, one which does not interfere with the cutting or chipping operation and the use of the hammer.

It is an object of the present invention to provide a simple and inexpensive safety guard which will encourage its use and protect other workmen in the immediate vicinity as well as the operator.

It is another object of the invention to provide a safety guard for use with chipping hammers and the like which will deflect the chips or other foreign particles downwardly, away from the work, immediately after they leave the surface thereof, thereby eliminating the danger of the chips piling up and obscuring the work.

It is a further object of the invention to provide a safety guard which will permit a clear vision of the working tool and the work at all times and, at the same time, provide a guard which is effective in its use.

Various other objects and advantages of this

invention will be more apparent in the course of the following specification and will be particularly pointed out in the appended claims.

In the accompanying drawing there is shown, for the purpose of illustration, one embodiment which my invention may assume in practice.

In this drawing:

Figure 1 is a side elevation of a pneumatic hammer in use, showing the improved safety guard of my invention incorporated therewith and the use thereof;

Figure 2 is an enlarged side elevation, partly in section, showing my improved safety guard assembled on the shank of the cutting tool;

Figure 3 is a plan view thereof;

Figure 4 is a plan view showing a slight modification thereof;

Figure 5 is a side elevation similar to Figure 2, showing a modified form of safety guard of my invention; and,

Figure 6 is a plan view thereof.

Referring more particularly to the drawing, the preferred embodiment of the safety guard of my invention as shown in Figures 1 and 2 of the drawing, comprises a longitudinally extending inherently resilient frame member 2 which is preferably made of spring steel or any other suitable resilient sheet metal. The inner end 3 of the frame 2 is securely attached to a pliable annular member, preferably a short length of rubber hose 4, by means of the rivet 5 or in any other suitable manner. The pliable member or rubber hose 4 should have an interior diameter slightly less than the shank 6 of the working tool 7 with which it is to be used as it is adapted to fit tightly therearound. Also, it is preferable that the inner end 3 of the frame 2 be disposed within the annular member or length of rubber hose between the same and the shank 6 of the working tool so as to aid in supporting the same. A portion of the frame 2 adjacent the inner end thereof is bent downwardly on each side thereof as at 8, so as to fit partially around the outer surface of the shank of the working tool so as to aid in preventing the frame 2 from twisting or turning relative thereto.

There is arranged toward the outer end of the frame 2, a relatively wide deflecting portion 9 of such width as to properly deflect the chips or foreign particles struck up by the particular working tool with which it is to be used. There is disposed in the top of the deflecting portion 9 substantially centrally thereof, a longitudinally extending opening 10 through which the workman is adapted to view the end of the working

tool and the workpiece. At the extreme outer free end of the frame 2 there is arranged an outwardly and downwardly bent portion 12 terminating in an upwardly curved end portion 13, which is adapted to rest on the surface of the 5 workpiece during the chipping operation.

In Figure 4, there is shown a slight modification of my invention. This construction is substantially the same as the preferred form which has been described, but in addition there is provided a transparent material, such as a wire mesh 14, which is arranged over the opening 10 in the deflecting portion 9 of the frame 2. The wire mesh may be welded or otherwise suitably attached to the frame with the mesh of the wire 15 being small enough to prevent the chips and other pieces of foreign particles from passing therethrough. A one-fourth inch wire mesh has been found to be satisfactory for most purposes as it permits a clear vision therethrough of the 20 end of the working tool and the workpiece and, at the same time, properly deflects the chips so as to protect the operator. A guard of such construction is preferable for use when extremely small chips are thrown off by the working tool.

In Figures 5 and 6 of the drawing, there is shown another modification of the safety guard of the present invention. In this construction, the frame member is made preferably of a piece of inherently resilient wire 15 properly bent upon itself, and formed into the shape as shown in Figure 6, or in any other suitable shape. The inner ends 16 of the wire are securely attached as before to an annular pliable member preferably a length of rubber hosing 17. The ends 16 of the wire preferably extend within the length of rubber hosing between the same and the shank 6 of the working tool 7, as in the preferred embodiment, and the ends are preferably bent upwardly as at 18 so as to be disposed in holes 19 arranged through the wall of the rubber hose so as to prevent displacement of the frame.

The outer free end of the wire is bent backwardly upon itself so as to provide a relatively wide loop portion 20. There is arranged over the loop portion 20 preferably a wire mesh 21 so as to provide a deflecting shield portion on the end of the frame. The outer free end of the loop portion 20 is preferably bent outwardly and downwardly as at 22 which is adapted to rest upon the surface of the workpiece during the chipping operation.

In operation, the pliable annular member or rubber hose 4 is slipped over the end of the working tool or chipping chisel with which the guard is to be used and properly positioned on the shank thereof so that the end of the working tool or chisel and the workpiece can be properly viewed through the opening in the same. In starting the working tool or chisel, it is usually positioned at a small angle with the vertical and in this position, the extreme outer free end of the shield, namely, the portion 13 as shown in the embodiment of Figures 1 through 4 of the drawing, and the portion 22 of the embodiment 65 as shown in Figures 5 and 6 of the drawing, extends a slight distance beyond the end of the cutting tool and point of cutting and will bear upon the surface of the workpiece. As the cutting operation progresses, the working tool of course is lowered and approaches the horizontal and the outer free end of the deflecting shield or guard is still maintained in contact with the surface of the workpiece due to the inherently 70 resilient characteristics of the frame. That is,

the guard is always maintained in its proper position over the point of cutting no matter at what angle the cutting tool is positioned, due to the resiliency of the frame. Thus, it will be seen that the chips or other foreign particles of metal strike the guard which obstructs the path with sufficient resistance to neutralize their outward force, and deflects them downwardly and outwardly, thus eliminating the same from being deflected toward the body of the operator or towards other workmen in the immediate vicinity of the cutting or chipping operation.

While I have shown and described an embodiment of my invention and several modifications thereof, it will be understood that these embodiments are merely for the purpose of illustration and description, and that various other forms may be devised within the scope of my invention, as defined in the appended claims.

I claim:

1. A safety guard for the use of workmen operating pneumatic chipping hammers and the like comprising a longitudinally extending inherently resilient deflecting shield member adapted to be positioned over the working tool of the hammer, a pliable annular member to which the inner end of said shield is securely attached, said annular member adapted to fit tightly around the shank of the working tool, and an outwardly and downwardly extending portion arranged on the outer free end of said shield which is adapted to rest upon the workpiece during the working of the tool and to be held thereagainst by the resilient action of said shield member, said outwardly and downwardly extending portion being constructed and arranged so that the same will rest upon the workpiece at a point beyond the working edge of the tool when the tool is substantially parallel to the surface of the workpiece and at all times when the tool is in use.

2. A safety guard for the use of workmen operating pneumatic chipping hammers and the like comprising a longitudinally extending inherently resilient deflecting shield member, said shield having an opening arranged therethrough in the top thereof adjacent its outer end so as to enable the workman to view the end of the working tool and the workpiece therethrough, a pliable annular rubber member to which the inner end of said shield is securely attached, said annular rubber member adapted to fit tightly around the shank of the working tool, and an outwardly and downwardly extending portion arranged on the outer free end of said shield member which is adapted to rest upon the workpiece during the working of the tool and to be held thereagainst by the resilient action of said shield member, said outwardly and downwardly extending portion being constructed and arranged so that the same will rest upon the workpiece at a point beyond the working edge of the tool when the tool is substantially parallel to the surface of the workpiece and at all times when the tool is in use.

3. A safety guard for the use of workmen operating pneumatic chipping hammers and the like, comprising a longitudinally extending inherently resilient frame member formed of wire, a wire mesh securely arranged on said wire frame member adjacent the outer free end thereof so as to provide a shield for deflecting foreign particles caused by the chipping operation and to enable the workman to view the end of the working tool and the workpiece therethrough, a pliable annular rubber member to which the inner end of said wire frame is securely attached, said annular

rubber member adapted to fit tightly around the shank of the working tool, and an outwardly and downwardly extending portion arranged on the extreme outer free end of said wire frame member which is adapted to rest upon the workpiece during the working of the tool and to be held thereagainst by the resilient action of said frame member, said outwardly and downwardly extending portion being constructed and arranged so that the same will rest upon the workpiece at a point beyond the working edge of the tool when the tool is substantially parallel to the surface of the workpiece and at all times when the tool is in use.

4. A safety guard for chipping tools and the like comprising a longitudinally extending inherently resilient deflecting shield member adapted to be positioned over a working tool, said shield member made from a piece of inherently resilient sheet material, means arranged in the outer free end of said shield for viewing the end of the tool and the workpiece therethrough, and a resilient rubber ring member having an inner diameter slightly less than the outer diameter of the shank of the tool around which it is adapted to tightly fit, the inner end of said shield member disposed within the rubber ring member to which it is securely attached and adapted to be disposed next to the shank of the tool so as to be securely supported with the outer free end of said shield member adapted to rest upon the workpiece during the use thereof and to be held thereagainst at all times due to the resiliency of the same.

5. A safety guard for chipping tools and the like comprising a longitudinally extending inher-

ently resilient deflecting shield member adapted to be positioned over a working tool, means arranged in the outer end of said shield for viewing the end of the tool and the workpiece therethrough, a resilient rubber ring member to which the inner end of said shield is securely attached, said ring member adapted to fit snugly and completely around the shank of the tool, and an outwardly and downwardly extending portion arranged on the outer free end of said shield, said outwardly and downwardly extending portion being constructed and arranged so that the same will rest upon the workpiece at a point beyond the working edge of the tool when the tool is substantially parallel to the surface of the workpiece and at all times when the tool is in use.

6. A safety guard for chipping tools and the like comprising a longitudinally extending inherently resilient deflecting shield member adapted to be positioned over a working tool, means arranged in the outer end of said shield for viewing the end of the tool and the workpiece therethrough, a resilient rubber ring member to which the inner end of said shield is securely attached, said ring member adapted to fit snugly and completely around the shank of the tool, an outwardly and downwardly extending portion arranged on the outer free end of said shield which is adapted to rest upon the workpiece at all times, and means carried by said shield which is adapted to cooperate with the working tool for preventing sidewise movement of the shield relative to the tool.

STEPHEN PLATECK.
